ATTORNEY

UNITED STATES PATENT OFFICE

EDWIN F. HUDDLE, OF ROCKFORD, ILLINOIS, ASSIGNOR TO J. I. CASE COMPANY, OF RACINE, WISCONSIN, A CORPORATION

MOWER

Application filed October 9, 1931. Serial No. 567,848.

The object of my invention is to provide simple and positive means whereby the shoe of a mower and the parts carried thereby will be readily detached from the shoe support 5 when the cutter-bar strikes obstructions in its path and caused thereby to swing rearwardly, thus preventing breakage of the mower parts, and which parts may again be re-connected in operable condition, without 10 the use of shear pins commonly employed for connecting the cutterbar to the shoe. The use of such pins is objectionable for the reason that a supply must be constantly present when mowing and also that as the pins 15 are usually of the same strength those of suitable character can only be approximately determined as to their resisting and breaking qualities, so that the shearing action of such pins is varied and at times unsatisfactory according to the degree of impact between the 20 cutterbar and the obstructions encountered in the field.

In the accompanying drawing, forming part hereof, Figure 1 is a fragmentary plan of that portion of a mower to which my improvement is applicable; Fig. 2, a detail section taken on the dotted line 2-2 in Fig. 1; and Fig. 3 is a detail section as seen when looking in the direction of the arrows 3-3 25 in Fig. 1.

In said drawing the numeral 5 indicates a shoe support embodying a sleeve 6 mounted on a shaft 7 in a well known manner, an arched hinge member 8 extending from the sleeve and terminating in a preferably integrally formed pin 10, the opposite side of the shoe support including a bearing 12, which latter is elongated for purposes of 30 stability in supporting the shoe 13, as will appear.

In said bearing 12 I pivotally mount an arm 14, the vertical shank 15 of which is secured by washers 16 and pins 17, as indicated in Fig. 2, and on said arm I mount the shoe bearing 13' adapted to pivot in relation to the shoe support 5. The cutter-bar 18 and guide member 19 are fixedly secured to the shoe, at 18', 19', while the guide member 20 is also secured to the shoe, the members 19, 20, 35 forming a guide through which the sickle-

head 21, sickle-bar 22 and pitman 23 reciprocate. Upon the shoe 13 I mount a keeper for the pin 10, preferably comprising the fixed jaw 25 and the hinged jaw 26, which latter is pivotally connected to the shoe at 27, said 55 jaws having their outer ends diverging as indicated in Fig. 3. These jaws and the shoe are connected by a bolt 28 having a coil spring 29 engaging its head 30 and the hinged jaw 26, so that the latter jaw will be urged 60 toward the jaw 25 for the purpose presently to appear.

As indicated in Fig. 1, the parts are in normal position for cutting, the shoe 13 being pivotally connected with its support 5 by the arm 14. When the sickle-bar strikes an obstruction said bar, the cutter-bar, guide members and parts supported by the shoe, as a unit, will swing rearwardly about the pivotal connection 15, the pin 10 at the moment 65 of impact being released from the jaws 25, 26, which pull away therefrom through the yielding action of the spring 29, which spring is adjusted so as to govern the amount of 70 resistance the cutter-bar must overcome before it disconnects. By tightening the nut on bolt 28 the spring will urge jaw 26 toward 75 jaw 25 with increased pressure, thereby causing the required resistance to the cutter-bar to be more than if said spring 29 is more 80 loosely adjusted. The shoe with its associated parts may then be re-connected by swinging the same forwardly, when the jaws of the keeper will snap onto the pin 10, and the entire assemblage thus secured in normal 85 cutting position. It will be also understood that the oppositely disposed arm 14 and pin 10, when the parts are in the position indicated in Fig. 1, constitute a pivotal connection 90

whereby the shoe and parts carried thereby may be swung vertically when so desired. It will thus be seen that I provide simple means for connecting the shoe and its support whereby horizontal and vertical adjustments of the cutter-bar may be performed, and that by employing the elongated bearing 12 in which to pivotally mount the shoe a stable connection is made for supporting the shoe and parts assembled therewith 100

against undue sagging as the mover traverses the field.

I claim as my invention:

1. In a mower, a shoe support having bearings at its opposite ends, a shoe pivotally mounted on said bearings for vertical adjustment, and means for releasing the shoe from one of said bearings whereby it may be pivoted in a horizontal direction about the opposite bearing on said shoe support.

10 2. In a mower, a shoe support including a sleeve, a bearing adjacent the sleeve, an arm pivotally mounted in said bearing, a shoe pivotally connected to the arm to swing vertically and horizontally, a bearing on the opposite end of the shoe, and means on the shoe normally engaging said latter bearing and releasable therefrom when the shoe is pivoted horizontally about said arm.

15 3. In a mower, the combination, with a shoe support, of an angulated arm mounted in said support, a shoe pivotally connected to the arm to swing horizontally and vertically, and means on the shoe normally engaging the support for releasing the shoe from the support to be swung horizontally on the arm.

20 4. In a mower, a shoe support including a vertical bearing, an arm including a vertical and a horizontal member pivotally mounted 30 in the bearing, a shoe connected to the arm, a keeper on the shoe, and means on the shoe support adapted to engage the keeper to normally secure the shoe in position and releasable from said keeper whereby the shoe may swing horizontally upon impact of part of the mower with obstructions in its line of travel.

25 5. In a mower, a shoe support having an arm, a shoe pivotally connected to the arm, a cutter-bar carried by the shoe, a yielding keeper mounted on the shoe opposite its pivotal connection with the support, and means for normally engaging the keeper to maintain the cutter-bar in cutting position and for releasing the shoe to swing horizontally when the cutter-bar strikes an obstruction.

30 6. In a mower having a shoe, a keeper on the shoe comprising jaws one of which is yieldingly mounted in relation to the other, and a shoe support having an arm pivotally connected to the shoe and having means engageable with and separable from the keeper whereby the shoe may be maintained in normal operable condition and also to be released 55 to swing horizontally upon striking an obstruction.

35 7. In a mower having a shoe, a keeper on the shoe, and a shoe support pivotally connected to the shoe and having means engageable with and separable from the keeper whereby the shoe may be maintained in normal operable condition and also to be released to swing horizontally upon its pivotal connection when striking obstructions.

8. In a mower having a shoe, a bearing on the shoe, a keeper on the shoe opposite the bearing, a shoe support, means pivotally connecting the shoe support to the shoe bearing, and means for detachably connecting the keeper to the shoe support, said shoe being adapted to swing vertically on said connecting means and horizontally in relation to the shoe support upon release of said detachable connecting means.

70 75 In testimony whereof I affix my signature.
EDWIN F. HUDDLE.
